US0D1033388S

(12) **United States Design Patent** (10) **Patent No.:** **US D1,033,388 S**
(45) **Date of Patent:** **** Jul. 2, 2024**

(54) **REMOTE CONTROLLER**

(71) Applicants: **Shenzhen Qianny Technology LTD**,
Shenzhen (CN); **Shenzhen Intellirocks Tech. Co., Ltd.**, Shenzhen (CN)

(72) Inventors: **Jinyu Pan**, Guangdong (CN); **Wenlong Wu**, Guangdong (CN)

(**) Term: **15 Years**

(21) Appl. No.: **35/517,527**

(22) Filed: **May 9, 2023**

(80) **Hague Agreement Data**

Int. Filing Date: **May 9, 2023**

Int. Reg. No.: **DM/229402**

Int. Reg. Date: **May 9, 2023**

Int. Reg. Pub. Date: **Jun. 16, 2023**

(51) **LOC (14) Cl.** **14-03**

(52) **U.S. Cl.**

USPC **D14/218**

Primary Examiner — Daniel J Domino

Assistant Examiner — Samina Vieth

(57) **CLAIM**

The ornamental design for a remote controller, as shown and described.

DESCRIPTION

1. Remote controller

1.1 : Perspective

1.2 : Perspective

1.3 : Front

1.4 : Back

1.5 : Left

1.6 : Right

1.7 : Top

1.8 : Bottom

The broken lines shown in the drawings are included for the purpose of illustrating portions of the remote controller that form no part of the claimed design.

1 Claim, 8 Drawing Sheets
